SANITARY PUMP ASSEMBLAGE

Vernon F. Dale and George Reed, Onalaska, Wis.,
assignors to The Bump Pump Co., La Crosse,
Wis., a corporation of Wisconsin

Application January 31, 1949, Serial No. 73,738

6 Claims. (Cl. 103—126)

1

Our invention relates in general to improvements in the art of transporting liquids through conduits or the like, and relates more specifically to various improvements in the construction and operation of liquid transfer pumps especially adapted to handle diverse commodities such as milk, syrups, and other beverages.

The primary object of the present invention is to provide an improved pump assemblage which is simple in construction, efficient in operation, and all parts of which are readily accessible for inspection.

Rotary pumps driven by electric or other kinds of motors through speed reducing gearing, have heretofore been used in many industries for the purpose of transporting various beverages such as milk, syrups, and the like. When handling commodities of this kind, it is essential that the pump assemblages be constructed so as to permit convenient internal and external cleaning in order to maintain the structures in highly sanitary condition. It is also desirable when utilizing positive displacement pumps for liquid, to make provision for preventing overloading of the units and excessive pressures in the liquid conducting conduits. Then too, when propelling certain types of commodity, it is desirable to transfer the liquid with positive action, at slow speed, and without excessive agitation, while also insuring self priming of the pumps. When the pump is located in close proximity to the speed reduction gearing, it is furthermore necessary to prevent lubricant escaping from the gear chamber, from entering the pump displacement chambers; and none of the prior motor driven rotary pump assemblages have effectively met all of these requirements.

It is therefore an object of our present invention to provide a simple, compact and durable positive displacement rotary pump unit, which embodies all of the above mentioned necessary and desirable features, and which is well protected against excessive pressure while also being readily cleanable.

Another important object of this invention is to provide various improvements in the details of construction of rotary double impeller liquid pumps, whereby such mechanisms may be quickly and conveniently assembled or dismantled, without disturbing the gearing which normally drives the impellers.

A further important object of the invention is to provide an improved rotary pump and gear housing assemblage wherein the pump is disposed closely adjacent to the gear casing, and

the latter may be provided with abundant lubrication without permitting escaping lubricant to enter the pump displacement chamber.

Still another object of our invention is to provide an improved seal for the shafts of rotary gear driven pumps or the like, which will effectively seal the pump displacement chamber while still permitting rapid dismantling and reassembly of the pump structure.

10 An additional object of the present invention is to provide improved mechanism for preventing attainment of dangerously high pressures in positive displacement rotary liquid pumps, which may be readily applied to new or old pump units, and which functions automatically to relieve abnormally high discharge pressures.

Another object of our present invention is to provide an improved sanitary liquid pump composed of relatively few simple parts, and which may be manufactured in various sizes and for diverse uses at moderate cost, while requiring minimum attention during normal operation and in order to maintain the structure in highly sanitary condition.

25 These and other objects and advantages of the invention will be apparent from the following detailed description.

A clear conception of the several features constituting our present improvement, and of the construction and operation of a typical pump unit embodying the same, may be had by referring to the drawing accompanying and forming a part of this specification wherein like reference characters designate the same or similar parts in the various views.

Fig. 1 is an exploded perspective view showing one of our improved gear driven sanitary pump units partially dismantled for cleaning purposes, and with the pump casing inverted;

40 Fig. 2 is an enlarged central longitudinally vertical section through the unit of Fig. 1, but showing the same fully assembled;

Fig. 3 is a section through the automatic flow control or pressure relief valve mechanism of the pump unit, the section having been taken along the line 3—3 of Fig. 2; and

45 Fig. 4 is a further enlarged central longitudinal section through one of our improved rotary shaft seals and through adjacent pump structure.

50 While the invention has been shown and described herein as being advantageously applicable to rotary gear driven liquid pumps having two cooperating double-lobe impellers, it is not our desire or intention to unnecessarily limit the utility of the improved features by virtue of

this restricted embodiment; and it is also contemplated that specific descriptive terms used herein be given the broadest possible interpretation consistent with the disclosure.

Referring to the drawing, the sanitary positive displacement liquid pump unit shown therein, comprises in general, a one-piece pump casing 6 having upper and lower bores 7, 8 respectively in open communication with each other, and also having intake and discharge conduits 9, 10 respectively communicating with the space between the bores 7, 8 on opposite sides of the casing 6; a pair of upper and lower double-lobe rotors or impellers 11, 12 rotatable within the casing bores 7, 8 respectively and normally intermeshing with each other between the conduits 9, 10, the impellers being rigidly secured to parallel driving shafts 14, 15 respectively projecting from corresponding sides thereof and each being provided with an enlargement 16 adjoining its rotor; a one piece gear housing 17 located at one side of the pump casing 6 and providing a gear chamber 18 which is accessible upon removal of a detachable closure plate 19 and which is also pierced by the parallel horizontal impeller shafts 14, 15; outer and inner pump closure heads 20, 21 coacting respectively with the outer flat surface of the casing 6 and with the adjacent inner flat surfaces of the casing 6 and housing 17; driving sleeves 23, 24 embracing the upper and lower shafts 14, 15 and being detachably secured thereto; intermeshing similar motion transmitting gears 25 secured to the adjacent sleeves 23, 24 within the chamber 18 by means of keys 26; and a power shaft 27 journalled in the housing 17 and having a pinion 28 secured to its inner end within the chamber 18 and drivingly coacting with a gear 29 keyed to the lower sleeve 24, while the outer end 30 of the shaft is flattened for connection to a driving motor by means of a coupling 31.

The two impellers 11, 12 of the pump may be formed integral with or firmly permanently secured to their respective driving shafts 14, 15 in any suitable manner, and when assembled for operation these impellers snugly coact with the casing bores 7, 8 and constantly contact each other during rotation thereof, so as to continuously withdraw liquid from a source of supply through the intake conduit 9 and to deliver the liquid under pressure through the discharge conduit 10. The casing end heads 20, 21 of the pump are also adapted to coact snugly with the opposite ends of the rotors or impellers 11, 12, and are capable of being clamped to the pump casing 6 and to the gear housing 17 through intervening gaskets, by means of studs 33 secured to the housing 17 and wing nuts 34 coacting with the outer threaded ends of the studs 33, as illustrated in Fig. 2. The pump may therefore be quickly dismantled without the aid of special tools by merely releasing the wing nuts 34 and by thereafter sliding the outer head 20, casing 6, and inner head 21 off of the studs 33 in succession, as exemplified in Fig. 1; and the rotor enclosure may be just as rapidly reassembled by reversing these operations, while two dowel pins 35 secured to the housing 17 and coacting with holes 36 insure proper assembly of these parts. It is to be noted that the removed pump casing 6 of Fig. 1 has been inverted in order to clearly illustrate the manner in which the impellers coact with the bores thereof, and the sealing gaskets have also been omitted for the sake of clearness.

The rotors or impellers 11, 12 of the pump together with their supporting and driving shafts 75

14, 15 may also be freely removed from the casing 6 when the outer end head 20 has been removed and the shafts are released by sliding these shafts 14, 15 longitudinally from within their respective driving sleeves 23, 24, and without disturbing these sleeves or the gears 26, 29 carried thereby. The shafts 14, 15 are each provided with a tapered section 37 adjoining the enlargement 16 thereon, and adapted to wedgingly engage similar tapers formed in the adjacent ends of the sleeves 23, 24, and the opposite outer end of each of these sleeves beyond the confines of the housing 17, is normally drivingly attached to the corresponding shaft 14, 15 by a key 38 formed integral with a collar 39 which embraces the reduced threaded end 40 of its shaft and coacts with the sleeve end, see Fig. 2. A manually operable clamping nut 41 coacts with each of the threaded outer shaft ends 40 and with the adjacent collar 39 to simultaneously hold the adjoining key 38 in place and to force the corresponding sleeve taper into snug frictional driving engagement with the adjacent shaft tapered section 37, thereby providing a positive but readily releasable driving connection between each rotor shaft 14, 15 and its embracing sleeve 23, 24.

Each of the sleeves 23, 24 is journalled for free rotation within the housing 17 by means of two anti-friction bearings 43, 44 which coact with shoulders on these sleeves so as to prevent longitudinal displacement or shifting thereof, see Fig. 2. While these bearings 43, 44 are shown as ball bearings, they may be of any other anti-friction type, and the bearing 43 nearest the pump is preferably of the double-ball or roller type due to the greater load to which it is normally subjected. The anti-friction bearings 43, 44 are exposed to the gear chamber 18 but are sealed from the ambient atmosphere by sealing rings 45; and the gear housing 17 is provided with an external drain passage 46 at its end nearest to the pump closure plate of head 21, in order to prevent lubricant which may escape past the adjacent sealing rings 45 from reaching the pump assemblage. The gear chamber 18 is also preferably provided at its lower portion with a lubricant supply and drain fitting 47, and with a vent plug 48 at its upper portion, the latter serving to relieve undesirable pressure which may result from overheating.

As previously indicated, the flattened outer end 30 of the power shaft 27 may be connected to an electric motor or other source of power by a coupling 31, and the medial portion of this shaft is journalled for free rotation in the gear housing 17, while its inner end carries the driving pinion 28 which meshes with the larger gear 29 within the chamber 18, thus providing speed reduction. The gear 29 may be drivingly attached to the lower sleeve 24 by means of the same key 26 which attaches the lower gear 25 thereto, and the upper gear 25 is likewise drivingly attached to the upper sleeve 23 by means of a shorter key 26. In order to prevent the gears 28, 29 from shifting along their respective supporting sleeves 23, 24 set screws 49 may be provided as depicted in Fig. 2; and the gears and pinions may be inserted and assembled within, or removed from the chamber 18 upon removal of the closure plate 19 after withdrawal of the lubricant with which this gear chamber should be abundantly supplied during normal operation of the unit. It is to be noted that all transmission gears are normally supported only by the sleeves 23, 24 so that the shafts 14, 15 may be withdrawn from

within these sleeves without disturbing the gearing, but the sleeves may also be inserted within or removed from the housing 17 by manipulating the seal rings 45.

In order to make doubly sure that no escaping lubricant will reach the pump displacement chambers, while still permitting quick assembly or dismantling of the pump, we also provide improved packing or sealing assemblages 50 surrounding each shaft enlargement 16, and the detailed construction of one of which are illustrated in Fig. 4. These packing assemblages are of like formation, each comprising a metal ring 52 having a wedge shaped transverse cross-section and coacting with a metal ring 53 having an L-shaped transverse cross-section along a plane surface 54 disposed perpendicular to the shaft axes; and a pair of resilient or rubber sealing rings 55, 56 each having circular transverse cross-section and coacting with the metal rings 52, 53 respectively and with adjacent pump structure. The ring 52 has a wedge surface 57 coacting with the rubber ring 55 to press the latter against the shaft 14, 15 and against the adjacent impeller or rotor 11, 12, thus causing these rings 52, 55 to normally revolve with the rotor and shaft assembly. The L-shaped ring 53 likewise coacts with the rubber ring 56 to press it against an annular lip 58 formed on the pump closure head 21, thus fixing these rings 53, 56 against rotation, so that the rings 52, 53 normally have snug sliding contact at the flat surface 54, and an effective seal is produced by the pliable or resilient rubber rings 55, 56 when the seal is assembled by merely inserting the adjacent shaft 14, 15 within its supporting sleeve 23, 24 and by causing the corresponding impeller 11, 12 to contact the end head 21. These sealing assemblages 50 may, however, be just as conveniently dismantled by withdrawing the impellers and shafts, as indicated in Fig. 1.

When the improved positive displacement pumps are operable under relatively high pressures, it is preferable to provide an automatic flow control or pressure regulating device, an improved version of which is shown in Fig. 3. This device consists primarily of an auxiliary hollow casing 60 secured to the outer pump head 20 by any suitable means such as cap screws 61, and adapted to connect the pump discharge conduit 10 with the pump intake conduit 9 through openings 62, 63 respectively formed in the head 20; a plunger 64 slideable within a bore 65 in the casing 60 and being snugly cooperable with the opening 62 to throttle the flow of by-passed liquid from the pump discharge to the intake; a pressure regulating cap 66 adjustable with the aid of screw threads 67 longitudinally of the casing bore 65; and a helical compression spring 68 surrounding a stem 69 formed on the plunger 64 and having its opposite ends secured to and coacting with the cap 66 and plunger 64. The cap 66 may be manipulated to cause the plunger 64 to enter the opening 62 more or less so as to cause excessive discharge pressure to be automatically released to the pump suction while the pump is operating, and the position of the cap 66 determines the magnitude of the discharge pressure at which the relief device will act.

During normal operation of our improved sanitary pump unit, and assuming the parts to have been properly assembled as in Fig. 2 with the gear chamber abundantly supplied with lubricant and the intake and discharge conduits 9, 10 connected respectively to sources of liquid supply and demand, when rotative power is applied to

the shaft 30, rotary motion is imparted from the pinion 28 to the lower sleeve 24 through the gear 29, and from the sleeve 24 to the upper sleeve 23 through the intermeshing gears 25. The keys 5 38, collars 39 and nuts 40 cooperate with the tapered portions 37 to positively transmit opposite rotary motion to the shafts 14, 15 and impellers 11, 12 thereby causing liquid to be constantly withdrawn by the revolving and coacting impellers from the intake conduit 9 and to be delivered under pressure into the discharge conduit 10. The pressure at which this delivery takes place, may be accurately controlled by adjusting the cap 66, and any abnormal pressure 10 rise occurring in the discharge line will be automatically relieved by the plunger 64 which will then be forced entirely out of the opening 62 and will permit liquid to by-pass from the pump discharge to the intake.

When it becomes desirable to clean the pump, it is only necessary to remove the thumb nuts 34 from the studs 33, and to thereafter successively remove the outer end head 20 and the rotor casing 6 of the pump assemblage, whereupon the impellers 11, 12 and their driving shafts 14, 15 may be quickly withdrawn upon release of the assembly 15 nuts 41 from the threaded shaft ends 40. This withdrawal of the shafts 14, 15 will also partially or completely remove the sealing assemblages 50, and the inner end head 21 may then 20 be finally removed to completely dismantle the pump. After the various parts of the pump have been inspected and thoroughly cleansed, they may 25 be just as quickly and conveniently reassembled 30 to restore the pump to operating condition, and in order to facilitate rapid cleaning, the intake and discharge conduits 9, 10 should preferably be provided with quick detachable couplings of well-known structure. The sleeves 23, 24 and the gears 35 40 45 50 associated with the housing 17 will not be disturbed during ordinary dismantling and reassembly of the pump; but if it becomes desirable to also dismantle these sleeves and gears, this may be readily accomplished by removing the lubricant and the closure plate 19, and by releasing the bearing confining rings 45 from the housing 17.

From the foregoing detailed description of the construction and functioning of our improved pump assemblage, it should be apparent that we have in fact provided a positive displacement rotary liquid pumping unit which is simple and exceedingly compact in structure and efficient in operation, and which may also be readily maintained in sanitary operating condition with minimum effort and loss of time. The sealing rings 55, 45, drain passage 46 and the packing assemblages 50 cooperate to effectively prevent escaping lubricant from entering the pump casing; and the improved mounting of the impeller shafts vastly 55 facilitates dismantling and reassembly of the pump without disturbing the gearing or the driving mechanism. the openings 62, 63 in the head 20 may be plugged and the casing 60 and associated parts may be omitted. The improved pump assemblages may be manufactured at moderate cost in various sizes and for diverse uses, and have proven highly satisfactory and reliable in actual operation with very little attention required. When used with certain commodities the parts exposed to the liquid are preferably formed of rust resistant material, and when operating at relatively slow speed the impellers 11, 12 will produce minimum agitation, but the pump is self priming at all times regardless of the speed of operation.

It should be understood that it is not desired to limit this invention to the exact details of construction or to the precise mode of operation of the typical pump herein shown and described, for various modifications within the scope of the appended claims may occur to persons skilled in the art.

We claim:

1. In a pump assemblage, an impeller casing, a unitary gear housing having integral end closure walls, one of which is secured directly to said casing, a pair of parallel sleeves journalled for rotation in said housing walls and spanning the interior of the housing but being held against longitudinal displacement, each of said sleeves having a central bore and an internal frusto-conical surface at the end of said bore nearest to said casing, intermeshing gears for rotating said sleeves, a shaft extending longitudinally through each of said sleeves and having opposite ends projecting beyond its sleeve into said casing and externally of said housing, each of said shafts snugly fitting the adjacent sleeve bore and having a medial frusto-conical outer surface likewise fitting the adjacent frusto-conical sleeve surface, coacting pump impellers permanently secured to the shaft ends disposed within said casing, and means manipulable from the exterior of said casing and housing for detachably drivingly connecting the external shaft ends with the adjacent ends of said sleeves and for forcing the complementary inner and outer frusto-conical surfaces together.

2. In a pump assemblage, an impeller casing, a unitary gear housing having integral end closure walls, one of which is secured directly to said casing, a pair of parallel sleeves journalled for rotation in said housing walls and spanning the interior of the housing but being held against longitudinal displacement, each of said sleeves having a central bore and an internal frusto-conical surface at the end of said bore nearest to said casing, intermeshing gears for rotating said sleeves, a shaft extending longitudinally through each of said sleeves and having opposite ends projecting beyond its sleeve into said casing and externally of said housing, each of said shafts snugly fitting the adjacent sleeve bore and having a medial frusto-conical outer surface likewise fitting the adjacent frusto-conical sleeve surface, coacting pump impellers permanently secured to the shaft ends disposed within said casing, and means manipulable from the exterior of said casing and housing for detachably drivingly connecting the external shaft ends with the adjacent ends of said sleeves and for forcing the complementary inner and outer frusto-conical surfaces together, said shafts being longitudinally removable from within said sleeves only upon release of said connecting means and without disturbing the sleeve driving gears.

3. In a pump assemblage, an impeller casing, a

unitary gear housing having integral opposite closure walls to one of which said casing is secured, a pair of parallel sleeves journalled for rotation in said housing walls and spanning the interior of said housing, each of said sleeves having a central bore and an internal frusto-conical surface at the end of said bore nearest to said casing, anti-friction bearings for said sleeves mounted in said walls and being formed to permit free rotation of the sleeves but positively preventing longitudinal displacement thereof, intermeshing gears carried by said sleeves within said housing for transmitting rotary motion from one sleeve to the other, a shaft extending longitudinally through each of said sleeves and having opposite ends projecting beyond its sleeve into said casing and externally of said housing, each of said shafts snugly fitting the adjacent sleeve bore and having a medial frusto-conical outer surface likewise fitting the adjacent frusto-conical sleeve surface, coacting pump impellers permanently secured to the shaft ends disposed within said casing, and means coacting with said shafts and the adjacent sleeves externally of said casing and said housing for detachably drivingly connecting the external shaft ends with the adjacent sleeve ends and for forcing the complementary inner and outer frusto-conical surfaces together.

4. In a pump assemblage, an impeller casing, a unitary gear housing having integral opposite closure walls to one of which said casing is secured, a pair of parallel sleeves journalled for rotation in said housing walls and spanning the interior of said housing, each of said sleeves having a central bore and an internal frusto-conical surface at the end of said bore nearest to said casing, anti-friction bearings for said sleeves mounted in said walls and being formed to permit free rotation of the sleeves but positively preventing longitudinal displacement thereof, intermeshing gears carried by said sleeves within said housing for transmitting rotary motion from one sleeve to the other, a shaft extending longitudinally through each of said sleeves and having opposite ends projecting beyond its sleeve into said casing and externally of said housing, each of said shafts snugly fitting the adjacent sleeve bore and having a medial frusto-conical outer surface likewise fitting the adjacent frusto-conical sleeve surface, coacting pump impellers permanently secured to the shaft ends disposed within said casing, and means coacting with said shafts and the adjacent sleeves externally of said casing and said housing for detachably drivingly connecting the external shaft ends with the adjacent sleeve ends and for forcing the complementary inner and outer frusto-conical surfaces together, said shafts with their impellers being axially removable from said sleeves only upon release of said connecting means and without disturbing said gears.

5. In a pump assemblage, an impeller casing, a gear housing having opposite end closure walls one of which is secured to said casing, parallel sleeves journalled in said housing walls and spanning the interior of the housing but being held against longitudinal displacement, each of said sleeves having a central bore and an internal frusto-conical surface at the end of said bore nearest to said casing, intermeshing gears for imparting rotation from one of said sleeves to the other, a shaft extending longitudinally through each of said sleeves and having opposite ends projecting beyond its sleeve into said casing and

externally of said housing, each of said shafts snugly fitting the adjacent sleeve bore and having a medial frustro-conical outer surface likewise fitting the adjacent frustro-conical sleeve surface, coaxing pump impellers secured to the shaft ends within said casing, and means manipulable from the exterior of said casing and housing for detachably drivingly connecting the external shaft ends with the adjacent ends of said sleeves and for forcing the complementary inner and outer frustro-conical surfaces together.

6. In a pump assemblage, an impeller casing, a gear housing having opposite end closure walls one of which is secured to said casing, parallel sleeves journaled in said housing walls and spanning the interior of the housing but being held against longitudinal displacement, each of said sleeves having a central bore and an internal frustro-conical surface at an end of its bore, intermeshing gears for imparting rotation from one of said sleeves to the other, a shaft extending longitudinally through each of said sleeves and having opposite ends projecting beyond its sleeve into said casing and externally of said housing, each of said shafts coaxing with the adjacent sleeve bore and having a medial frustro-conical outer surface snugly fitting the adjacent frustro-conical sleeve surface, coaxing pump impellers secured to said shaft ends within said casing, and means manipulable from the exterior of said casing and housing for drivingly connecting the external shaft ends with the adjacent sleeve ends and for forcing the complementary inner and outer frustro-conical surfaces together.
